US00D578918S

(12) **United States Design Patent**
Aninye

(10) **Patent No.:** **US D578,918 S**
(45) **Date of Patent:** **** Oct. 21, 2008**

(54) **OFFENDER MONITOR**

(75) Inventor: **Steve Aninye**, Alpharetta, GA (US)

(73) Assignee: **Omnilink Systems, Inc.**, Alpharetta, GA (US)

(**) Term: **14 Years**

(21) Appl. No.: **29/279,448**

(22) Filed: **May 1, 2007**

(51) **LOC (8) Cl.** **10-05**

(52) **U.S. Cl.** **D10/104**

(58) **Field of Classification Search** **D10/104, D10/106; D30/151, 152; 600/508; 340/573.1**
See application file for complete search history.
